BASEBOARD RADIATOR

John W. Turner, Detroit, Mich., assignor to
 United States Radiator Corporation, Detroit,
 Mich., a corporation of New York

Application September 23, 1946, Serial No. 698,830

8 Claims. (Cl. 257—133)

1

The present invention relates to a baseboard radiator.

It is an object of the present invention to provide a heating radiator adapted to be installed in place of the conventional baseboard found in houses and which will occupy substantially the same space as the conventional baseboard. It is a further object of the present invention to provide an improved baseboard radiator capable of operating as a convector as well as a radiator. It is a further object of the present invention to provide a baseboard radiator characterized by the relative economy of material, the simplicity and economy of its manufacture, and its improved construction resulting in the formation of the essential elements thereof from sheet metal.

It is a feature of the present invention to provide a heating radiator characterized by the provision of longitudinally extending channels in the front plate by bending the material of the plate, and the provision of transversely extending channels in the rear plate formed by bending the plate, whereby upon assembly, each of the plates serves to close the channels formed in the other plate so as to define interior passages in the completed radiator.

Other objects and features of the invention will become apparent as the description proceeds, especially when taken in conjunction with the accompanying drawings, wherein:

Figure 1 is a rear elevation of the improved radiator structure;

Figure 2 is a plan view of the improved radiator structure;

Figure 3 is an end elevation of the improved radiator structure;

Figure 3A is a fragmentary vertical section through a somewhat modified form of radiator structure;

Figure 4 is a transverse vertical section through a radiator of the type shown in Figures 1-3 combined with a convector, the section through the combined structure being taken at a position corresponding to the section line 4—4 through the radiator shown in Figure 2;

Figure 5 is a transverse vertical section through a heating radiator of the type shown in Figures 1-3 combined with a convector and through the wall structure on which it is mounted, the section through the combined structure being taken at a point corresponding to the section line 5—5 through the radiator shown in Figure 2; and

Figure 6 is a fragmentary front elevation of a portion of the baseboard radiator mounted in place and showing cooperating structure adapted to cause the radiator to function as a convector.

Referring now to Figures 1, 2 and 3, there is illustrated a baseboard radiator structure 30 comprising a front plate 10, a rear plate 11, and

2

end plates 12. As best seen in Figure 3, the front plate 10 is bent to provide a central depressed portion 13 having extending along longitudinal edges thereof forwardly extending bent portions 14 and rearwardly extending flanges 15. The forwardly bent portion 14 and the flanges 15 define inwardly open channels 16. Before the bending operation, the edges of the front plate 10 may have notches formed therein to provide tabs 17 of the conformation shown in Figure 2.

The rear plate 11 is provided with a plurality of reverse bends which provide alternately inwardly and outwardly facing channels 20 and 21. The bottoms of the outwardly facing channels 21 are flat and of substantial extent, as indicated at 22 in Figure 2. Preferably the bottoms 23 of the inwardly opening channels 20 are also flat and of substantially the same area as the bottoms 22 of the outwardly facing channels 21. At the ends, the plate 11 is provided with flat portions 24 which are coplanar with the bottoms 23 of the inwardly facing channels 20.

It will be appreciated that the specific shapes of the front and rear plates as just described are particularly well adapted to be formed by bending sheet metal, since all of the bends formed in each of the plates are along parallel lines.

In order to assemble the front and rear plates 10 and 11, they are brought together so that the flanges 15 which extend rearwardly from the front plate 10 overlie the tops and bottoms of the inwardly facing channels 20. As best seen in Figure 3 and for simplicity of assembly, the rear plate 11 may be of somewhat greater height than the front plate 10 after it has been bent as illustrated in this figure. Therefore the assembly operation results in the insertion of the tabs 17 into the inwardly facing channels 20 at top and bottom of the rear plate 11. The rear edge of the flanges 15 is then welded as indicated at 25 to the rear plate 11. The depth of the alternately inwardly and outwardly facing channels 20 and 21 of the rear plate 11 is such that the flat bottoms 22 of the outwardly facing channels engage the depressed central portion 13 of the front plate 10. These engaging surfaces are also welded together preferably by spot welding.

In Figure 3A there is illustrated a somewhat modified construction. In this figure the radiator is intended to function only as a radiator and not as a combined radiator and convector. Accordingly, it is unnecessary to leave open the rearwardly facing channels 21a, and the flange 15a of the front plate 10a need not be provided with the cut-out portions forming tabs 17 illustrated in Figure 2. Instead, the flange 15a is continuous and is adapted to overlie the top of the rear plate 11a. The plates 10a and 11a are secured together in a pressure tight sealed relation as by con-

tinuous welding as indicated at 25a. It will be appreciated that the structure illustrated in Figure 3 is intended to provide vertically extending channels 21 through which heated air flows by convection, as will subsequently be described in detail, whereas in the radiator illustrated in Figure 3A the similar vertically extending passages are closed at their tops and bottoms by the rearwardly extending flanges 15a.

It will be appreciated that the assembly of the front and rear plates as just described lends itself to the production of elongated radiators and the method may therefore be practiced to produce radiators of any desired length. Each radiator unit is completed by providing end plates 12 having the conformation illustrated in Figure 3 which permit them to be inserted into the ends of the elongated radiator structure and welded in place as indicated at 26 (Figure 2). The end plates 12 are relatively enlarged at either end thereof to correspond to the inwardly opening longitudinally extending channels 16 formed in the front plate 10 and pipe openings are formed therein as indicated at 27 for connection as by threading, welding, or the like to suitable conduit means for supplying heating fluid to the radiators. It will be appreciated that if the radiator is associated with a heating system of a type which does not require the plurality of openings thus provided, any not employed in the heating system may be closed by a suitable threaded plug. In addition, if desired, smaller openings (not shown) may be provided in the end plates 12 for connection of suitable air vents.

Attention is drawn to the fact that each of the plates has inwardly opening channels formed therein and each plate serves as a means for closing the sides of the channels in the other plate so as to form longitudinal or transverse passages therein. Therefore, in the completely assembled radiator the channels 16, as closed by the rear plate 11, define longitudinally extending passages 28. In like manner the inwardly opening channels 20 formed in the rear plate 11, as closed by the front plate 10, provide transversely or vertically extending passages 29. It will further be apparent that each of the vertically extending passages 29 thus formed communicates freely at either end thereof with the longitudinally extending passages 28. Therefore the transversely or vertically extending passages 29 may be considered as connected between headers formed by the longitudinally extending passages 28.

The present structure may conveniently be formed of relatively light gauge sheet metal, and the particular design resulting in the formation of both longitudinally and transversely extending bends in the complete device renders the assembled radiator quite rigid and very strong. It will be observed that the radiator as illustrated and described has what may be called bilateral symmetry, which further simplifies its production. Due to the fact that the front end rear plates are welded together not only along their edges but also at a number of closely spaced points throughout the length of the radiator, the entire radiator is substantially stiffened against distortion under pressure and the design is such that even though light gauge metal is employed the radiator still has sufficient strength to withstand not only high normal working pressures but also substantially higher testing pressures to which it may be subjected. It will be appreciated that the welds between the edges of the front and rear plate are continuous, whereas the welds pro-

vided to secure the bottoms 22 of the outwardly facing channels 21 to the depressed portion 13 of the front plate are preferably separated spot welds.

It is contemplated that the structure just described shall be dimensioned such that it is not substantially larger than the conventional baseboard employed in housing and that it may be substituted therefor to provide an efficient heat distributing structure without occupying useful space within the enclosure being heated.

The radiator structure just described is adapted to operate as a radiator without further modification and may be mounted along the lower edge of the wall of an enclosure to be heated and connected to suitable conduits for supplying a heating medium thereto. However, the structure thus described is particularly well adapted to be mounted in such a way as to perform the additional function of a heat convector, as will now be described.

As best seen in Figure 4, the radiator 30 may be secured to a back plate 31 which has forwardly extending top and bottom flanges 32 and 33, respectively. Preferably the height of the back plate 31 is sufficiently greater than the height of the radiator 30 so as to provide a substantial space between the top of the radiator 30 and the top flange 32 and between the bottom of the radiator 30 and the bottom flange 33. The radiator 30 may be secured to the back plate 31, and for this purpose the flat bottoms 23 of the inwardly facing channels 20 may be plug welded as indicated at 34 or otherwise secured to the flat surface of the plate 31. It will be appreciated that this assembly of the radiator 30 with a back plate 31 results in the closing of the outwardly open channels 21 to form vertically extending passages as indicated at 35 in Figure 4. With the assembly as illustrated in Figure 4, it will be appreciated that when heating medium is supplied to the radiator a circulation of air will be induced to enter the lower end of the passages 35 and to flow upwardly therethrough to be discharged through the space between the upper flange 32 and the top of the radiator.

Referring now to Figures 5 and 6, there is illustrated the complete assembly of the radiator with the associated convector structure in a building. In this case there is illustrated generally at 40 a building wall comprising sheeting 41, insulation 42, a vapor barrier 43 and lath and plaster 44. In these figures the structure of the back plate 31 is somewhat modified, the flanges 33 having their forward edges bent inwardly and pierced to provide a grill structure 45.

As a practical embodiment of the present invention, it has been found that a radiator having a height of about seven inches and an over-all thickness measured outwardly from the back plate thereof of about an inch and a half is suitable. The height may be varied considerably, and may be twelve inches or more. It will be appreciated of course that these dimensions may be modified as desired, but the specific dimensions just outlined have been given in order to emphasize the fact that the over-all dimensions of the complete radiator either with or without its associated convector structure are not substantially different from the dimensions of a conventional baseboard, or at least are such that the structure may be substituted for baseboards. Irrespective of the height of the structure, its thickness is such that it does not project into the room substantially beyond a point to which con-

ventional baseboard structure would extend, so that there is no loss of space in the room while at the same time the floor of the room is unmodified.

While reference was previously made to the provision of notches in the edges of the front plate 10 to provide tabs 17 to close the upper and lower ends of the inwardly facing channels 29, it will be appreciated that where the radiator is to be used solely for radiation without employing its convector function, the edges of the front plate 10 need not be notched and may overlie the top and bottom edges of the rear plate 11 so as to close the tops and bottoms of both the inwardly and outwardly facing channels formed therein.

The novel radiator disclosed herein may be employed with steam, vapor, or hot water as the heating medium and its method of connection to the heating system will vary in accordance with conventional plumbing practice. Thus for example, if the radiator is employed with hot water, connection of the hot water will normally be to the lower opening in the end closure plate 12, and the return pipe will be connected to the upper opening therein. If employed with steam or vapor the connections will normally be reversed.

The specific material employed in the production of the improved radiators may of course be varied as desired, but preferably in all cases a relatively ductile sheet material capable of being welded is preferred. In any case, the complete radiator will be relatively light, particularly when considered from the viewpoint of the strength and stiffness or rigidity of the completed device.

While there is illustrated and described in considerable detail a preferred embodiment of the present invention, it will be appreciated that this full disclosure has been made solely to enable those skilled in the art to practice the invention, the scope of which is indicated by the appended claims.

What I claim as my invention is:

1. Heating structure comprising a flat vertically extending plate having narrow flanges extending outwardly from the top and bottom thereof, the bottom flange being adapted to rest on the floor of a space to be heated, an elongated radiator of a height less than the height of said plate and of a thickness substantially equal to the width of said flanges, said radiator being secured to the vertical portion of said plate and supported thereby spaced from the floor and from said flanges to provide for air circulation over the rear of said radiator, the rear surface of said radiator having vertical channels therein which are closed rearwardly by said plate to provide vertical passages for convective flow of air over the back of said radiator.

2. Heating structure comprising a flat vertically extending plate having narrow flanges extending outwardly from the top and bottom thereof, the bottom flange being adapted to rest on the floor of a space to be heated, an elongated radiator of a height less than the height of said plate and of a thickness substantially equal to the width of said flanges, said radiator being secured to the vertical portion of said plate and supported thereby spaced from the floor and from said flanges to provide for air circulation over the rear of said radiator, and grills closing the space between the forward edge of said flange and the top of said radiator, and between the bottom edge of said radiator and the floor.

3. Heating structure comprising a flat vertically extending plate having narrow flanges extending outwardly from the top and bottom thereof, said bottom flange being adapted to rest upon the floor of a space to be heated, an elongated radiator of a height less than the height of said plate and of a thickness substantially equal to the width of said flanges, said radiator being secured to the vertical portion of said plate and supported thereby spaced from the floor and from said flanges to provide for air circulation over the rear of said radiator, the outer edges of said flanges having vertically extending grill portions extending to close the spaces between the top and bottom edges of said radiator and said flanges.

4. Heating structure comprising a front plate of sheet metal having its top and bottom edge portions bent forwardly and then rearwardly to provide a central flat depressed portion extending from end to end thereof, a rear closure plate of sheet metal having a plurality of reverse bends providing alternate forwardly and rearwardly facing vertical channels, the top and bottom edges of said front plate being notched to conform to the shape of said rear plate and to overlie the forwardly facing channels, and being secured to the top and bottom edge of said rear plate, the bottoms of the rearwardly facing channels of said rear plate being secured to the rear surface of the flat central depressed portion of said front plate, the forwardly and then rearwardly bent edge portions of said front plate providing horizontally extending passages within the structure, end closure plates secured at their edges to the edges of said front plate and rear closure plate, pipe receiving openings in one of said end closure plates in at least partial alignment with said horizontally extending passages, and a backing plate of sheet metal having a flat portion secured to the bottom of the forwardly facing channels of said rear plate to close the rear side of the rearwardly facing channels, said backing plate having a forwardly extending flange along its top edge spaced from an overlying the structure comprised by said front and back plate the horizontally extending top and bottom passages providing for the flow of heating medium, the forwardly facing vertical channels formed in the rear closure plate providing for vertical flow of the heating medium between the top and bottom horizontal passages, the rearwardly facing vertical channels provided intermediate the rear closure plate and the backing plate providing for convection flow of air therethrough.

5. Heating structure comprising a front plate of sheet metal having its top and bottom edge portions bent forwardly and then rearwardly to provide a central flat depressed portion extending from end to end thereof, a rear closure plate of sheet metal having a plurality of reverse bends providing alternate forwardly and rearwardly facing vertical channels, the top and bottom edges of said front plate being notched to conform to the shape of said rear plate and to overlie the forwardly facing channels, and being secured to the top and bottom edge of said rear plate, the bottoms of the rearwardly facing channels of said rear plate being secured to the rear surface of the flat central depressed portion of said front plate, the forwardly and then rearwardly bent edge portions of said front plate providing horizontally extending passages within the structure, end closure plates secured at their edges to the edges of said front plate and rear

closure plate, pipe receiving openings in one of said end closure plates in at least partial alignment with said horizontally extending passages, and a backing plate of sheet metal having a flat portion secured to the bottoms of the forwardly facing channels of said rear plate to close the rear side of the rearwardly facing channels, said backing plate having forwardly extending top and bottom flanges spaced vertically from the top and bottom of the structure comprised by said front and back plate the horizontally extending top and bottom passages providing for the flow of heating medium, the forwardly facing vertical channels formed in the rear closure plate providing for vertical flow of the heating medium between the top and bottom horizontal passages, the rearwardly facing vertical channels provided intermediate the rear closure plate and the backing plate providing for convection flow of air therethrough.

6. An elongated radiator formed of sheet metal and comprising a front sheet having a flat central portion extending the full length thereof, the top and bottom portions of said sheet being shaped along longitudinally extending lines to provide forwardly extending, rearwardly open channels at the top and bottom thereof, the top and bottom edges of said sheet extending rearwardly of the plane of said flat central portion, a rear sheet formed along vertically extending lines to provide vertical, alternately forwardly and rearwardly facing channels extending the full height thereof, the top and bottom edges of said front sheet being notched to interfit with the vertically extending forwardly facing channels in said rear sheet so as to close the tops and bottoms of said last mentioned channels and to leave the rearwardly facing channels in said rear sheet open for convection flow of air and being secured in sealing relation to the top and bottom edges of said rear sheet to close the tops of the forwardly facing channels therein, the bottoms of the rearwardly facing channels of the rear sheet being secured to the flat central portion of said front sheet, and end closures for said radiator secured in sealing relation at the ends thereof to both said front and rear sheets, at least one of said end closures having openings therein aligned with the longitudinally extending passages formed by the rearwardly open channels in said front sheet.

7. An elongated radiator formed of sheet metal and comprising a front sheet having a flat central portion extending the full length thereof, the top and bottom portions of said sheet being shaped along longitudinally extending lines to provide forwardly extending, rearwardly open channels at the top and bottom thereof, the top and bottom edges of said sheet extending rearwardly of the plane of said flat central portion, a rear sheet formed along vertically extending lines to provide vertical, alternately forwardly and rearwardly facing channels extending the full height thereof, the top and bottom edges of said front sheet being notched to interfit with the vertically extending forwardly facing channels in said rear sheet so as to close the tops and bottoms of said last mentioned channels and to leave the rearwardly facing channels in said rear sheet open for convection flow of air and being secured in sealing relation to the top and bottom edges of said rear sheet to close the tops of the forwardly facing channels therein, the bottoms of

the rearwardly facing channels of the rear sheet being secured to the flat central portion of said front sheet, and end closures for said radiator secured in sealing relation at the ends thereof

5 to both said front and rear sheets, at least one of said end closures having openings therein aligned with the longitudinally extending passages formed by the rearwardly open channels in said front sheet, and a backing plate secured to

10 said rear sheet in position to close the open side of the rearwardly facing channels therein to form vertical air passages.

8. An elongated radiator formed of sheet metal and comprising a front sheet having a flat central portion extending the full length thereof, the top and bottom portions of said sheet being shaped along longitudinally extending lines to provide forwardly extending, rearwardly open channels at the top and bottom thereof, the top and bottom edges of said sheet extending rearwardly of the plane of said flat central portion, a rear sheet formed along vertically extending lines to provide vertical, alternately forwardly and rearwardly facing channels extending the full height thereof, the top and bottom edges of said front sheet being notched to interfit with the vertically extending forwardly facing channels in said rear sheet so as to close the tops and bottoms of said last mentioned channels and to leave the rearwardly facing channels in said rear sheet open for convection flow of air and being secured in sealing relation to the top and bottom edges of said rear sheet to close the tops of the forwardly facing channels therein, the bottoms of the rearwardly facing channels of the rear sheet being secured to the flat central portion of said front sheet, and end closures for said radiator secured in sealing relation at the ends thereof to both said front and rear sheets, at least one of said end closures having openings therein aligned with the longitudinally extending passages formed by the rearwardly open channels in said front sheet, and a backing plate secured to said rear sheet in position to close the open side of the rearwardly facing channels therein to form vertical air passages.
